WEEDING TOOL

Lee B. Grover, Rte. 1, Box 80, Marengo, Ill.

Filed Dec. 19, 1961, Ser. No. 67,981

Term of patent 14 years

(Cl. D35—2)

FIG. 1 is a side elevational view of a weeding tool showing my new design;

FIG. 2 is an end elevational view thereof;

FIG. 3 is an enlarged perspective view thereof taken from the side shown in FIG. 1; and

FIG. 4 is an enlarged perspective view thereof taken from the side opposite that shown in FIGS. 1 and 3.

The handle is broken away in FIGS. 2, 3 and 4 for convenience of illustration.

The characteristic features of my design reside in the cutter head as shown.

I claim:

The ornamental design of a weeding tool, substantially as shown and described.
